UNITED STATES PATENT OFFICE.

EDWARD LEE KING, OF CHARLESTON, ILLINOIS.

SHADE-BRACKET.

1,072,739.

Specification of Letters Patent. Patented Sept. 9, 1913.

Application filed November 23, 1912. Serial No. 733,150.

To all whom it may concern:

Be it known that I, EDWARD LEE KING, a citizen of the United States, residing at Charleston, in the county of Coles and State of Illinois, have invented new and useful Improvements in Shade-Brackets, of which the following is a specification.

The invention relates to shade roller brackets and has for its primary object to 10 provide a bracket wherein the same may be mounted upon a window frame, door, or the like, so as to support a shade roller, the same being held against accidental displacement when operated.

15 Another object of the invention is the provision of a shade roller bracket in which the pintle for supporting the shade roller is spring held, so that the shade may be readily wound upon and unwound from the 20 roller, the spring being particularly mounted within the bracket so that when the shade is wound up upon the roller the tension upon the said spring is relieved therefrom, thereby obviating the breaking of the spring.

25 A further object of the invention is the provision of a curtain shade bracket in which the spring is held thereby, obviating the necessity of mounting the spring within the shade roller, yet the roller can be tensioned for the winding of the shade thereon.

30 A still further object of the invention is the provision of a shade roller bracket which is simple in construction, thoroughly reliable and efficient in its purpose, and inexpensive in manufacture.

With these and other objects in view the invention consists in the construction, combination and arrangement of parts as will be hereinafter more fully described, illustrated in the accompanying drawing, and pointed out in the claims hereunto appended.

In the drawings:—Figure 1 is a front elevation of a shade roller mounted in brackets 45 constructed in accordance with the invention. Fig. 2 is a side elevation of one of the brackets. Fig. 3 is a side elevation of the other bracket. Fig. 4 is a sectional view on the line 4—4 of Fig. 2. Fig. 5 is a sectional view on the line 5—5 of Fig. 3. Fig. 6 is a view similar to Fig. 2, looking toward the opposite side of the bracket, with the side cap removed.

Similar reference characters indicate corresponding parts throughout the several views in the drawing.

Referring to the drawings by numerals, 10 designates an ordinary shade roller carrying at one end a stud spindle 11, while mounted at the opposite end of the said 60 roller is a squared stud spindle 12, both of which are rigidly secured to the ends of the roller so as to turn therewith, and are adapted for engagement in shade roller brackets presently described. The shade roller 65 brackets 13 and 14, respectively, each comprises an elongated base 15 from which projects a web 16 having integrally formed therewith a circular shaped housing 17 in which are detachably engaged removable 70 side caps 18 and 19, respectively, the cap 19 being formed with a knob 20 projecting outwardly therefrom, while the cap 18 is provided with a central aperture 21. In both of the housings 17 are rotatably mounted arbors 22 and 23, respectively, in which are engaged the pintles 11 and 12, the said arbors being provided with sockets 24 correspondingly shaped to the said pintles 11 and 12 for receiving the same. These arbors 22 and 23 are projected through the holes 21 in the cap 18 and have their bearings in walls 25 integrally formed with the housing 17 internally thereof. Surrounding the arbor 22 is a coiled winding and unwinding spring 26, one end of which is fixed to the said arbor 22, while its opposite end is suitably fixed to the inner periphery of the housing 17 so that on the turning of the arbor 22 in one direction the spring will 80 become wound, thereby tensioning the shade roller so that on the unwinding of the spring, the shade, (not shown), ordinarily mounted upon the roller, will become wound thereon, but on the winding of the spring 90 the said shade will unwind therefrom, this being accomplished by pulling upon the shade in the ordinary well-known manner.

Surrounding the arbor 23 and working against the wall 25 in the housing 17 containing the said arbor is a coiled compression spring 27, the same being also designed to work against a shoulder 28 formed on the arbor, and in this manner the arbor 23 can be retracted against the spring 27 so 100 that the pintles 11 and 12 of the shade roller 10 can be engaged in the sockets 24 in both arbors 22 and 23, respectively. The cap 18 on the housing 17 containing the arbor 23 is 105 formed with a recess 29 which permits the arbor 23 to become displaced within the said housing 17 against the tension of the spring 110

27, and thereby permitting the easy mounting of the shade roller 10 in the brackets, as will be clearly apparent.

Fixed to the inner end of the arbor 22 is 5 a disk 30, on which are pivoted diametrically opposed ratchet dogs 31, each of which is adapted to engage in a notch 32 formed in a central lug 33 projecting from the inner side of the cap 18, and in this manner the 10 arbor 22 can be locked under the tension of the spring 26 for sustaining the shade unwound from the roller 10 at any desirable extent, that is to say, in other words, the shade can be adjusted as usual and held in 15 such adjusted position on the roller 10 supporting the same.

From the foregoing it is thought that the construction and manner of operation of the device will be clearly understood, and 20 therefore a more extended explanation has been omitted.

What is claimed is:—

1. A shade roller support comprising a pair of brackets each formed with a base, 25 a circular shaped housing supported by the base, caps closing opposite sides of each

housing, an arbor rotatably journaled in one of the caps, means for tensioning each of the arbors, and means connected with one of the arbors and engageable with one of the caps for locking the said arbor in adjusted position against the tension of the tension means acting thereon.

2. A shade roller support comprising a pair of brackets each formed with a base, 35 a circular shaped housing supported by the base, caps closing opposite sides of each housing, an arbor rotatably journaled in one of the caps, means for tensioning each of the arbors, means connected with one of the arbors and engageable with one of the caps for locking the said arbor in adjusted position against the tension of the tension means acting thereon, and bearings formed in the housing and supporting the inner- 40 most end portions of the arbors.

In testimony whereof I affix my signature in presence of two witnesses.

EDWARD LEE KING.
